UNITED STATES PATENT OFFICE.

FRANK J. MACDONALD, OF AKRON, OHIO, ASSIGNOR TO THE B. F. GOODRICH COMPANY, OF NEW YORK, N. Y., A CORPORATION OF NEW YORK.

METHOD AND APPARATUS FOR LINING RECEPTACLES.

1,399,780.

Specification of Letters Patent. Patented Dec. 13, 1921.

Application filed June 8, 1921. Serial No. 476,085.

To all whom it may concern:

Be it known that I, FRANK J. MACDONALD, a citizen of the United States, residing at Akron, in the county of Summit and State 5 of Ohio, have invented a certain new and useful Method and Apparatus for Lining Receptacles, of which the following is a specification.

This invention relates to the art of lining 10 hollow objects or receptacles, and especially metal receptacles, with a plastic material. As herein illustrated, my invention is adapted to compress a lining of uncured hard-rubber compound upon the walls of a foraminous 15 bowl such as is used for spinning artificial silk. It is desirable that high and substantially equal pressure be applied to all parts of the rubber lining to cause it to conform and adhere firmly to the bowl and interlock 20 with the recesses or apertures therein. Heretofore, so far as I am aware, this work has been done by hand, the lining being pressed in with a hand roller.

The object of my invention is to save time 25 and labor in performing this work and to obtain a better product.

Of the accompanying drawings:

Figure 1 is a plan view of a preferred embodiment of my invention. 30 Fig. 2 is a side view partly in section on line 2-2 of Fig. 1 and with parts broken away.

Fig. 3 is a perspective view of a part of the device.

35 Fig. 4 is a perspective view of a spinning bowl, before application of the lining.

Fig. 5 is a section of a part of the finished product.

Referring to the drawings:

40 The apparatus comprises a base plate 10 upon which is mounted an upright cylindrical wooden block or form 11 formed with an axial aperture 11^a in extension of an aperture 12 through said base plate. 13 is an 45 air or steam supply pipe threaded into said aperture 12.

A hat-shaped, elastic bag or diaphragm 14 formed preferably of an outer ply of rubberized fabric 15 and an inner ply 16 of rubber (Fig. 3), the closed end of said bag containing an embedded metal reinforcing plate 17 and the margin of said bag being formed with bolt holes 18, 18, is inverted 50 over the block 11 and its brim-like margin 55 is sealed down to the base plate 10 by a

clamping ring 19. The warp and weft of the fabric 15 preferably run obliquely on the side walls of the bag, as shown, in order that it may be more easily elongated or expanded laterally. 60

20 is an annular plate resting upon the clamping ring 19, and 21 is an upwardly flared, metal, collar-like guard mounted upon the annular plate 20 and surrounding the work at a distance therefrom. 65

22 is a metallic spinning bowl of goblet shape formed with a hollow stem and in this instance with a plurality of apertures, 23, 23, through its walls, causing said walls to present an uneven or broken surface. 24 70 (Fig. 2) is a lining of uncured rubber compound in position in said bowl and folded over the rim thereof as shown at 25, 25, the bowl being inverted over the bag 14 and resting upon the annular plate 20. 75

A flat annulus of wood 26 loosely surrounds the stem of the inverted bowl and rests upon the shoulder thereof. 27 is a downwardly flared, annular, metal guard secured to the wooden annulus 26 by screws 80 27^a, 27^b, its lower edge approximately meeting the upper edge of the guard 21. 28 is a handle for the guard 27 and wooden annulus 26.

A hand operated cross-head 29 is provided 85 for holding the inverted bowl against the plate 20, said cross-head being formed of two generally parallel bars converging and secured together near one end, at 30, their opposite ends being hinged at 31 to a block 90 32, slidably mounted on the reduced upper end of a standard 33 mounted upon the base plate 10.

34 is a compression spring upon said reduced upper end of the standard 33, adapted 95 to press the block 32 upward to prevent cramping of the cross-head against the annulus 26 as it is closed upon the latter, and 35, 35 are adjustment nuts threaded upon said reduced end and adapted to force the 100 block 32 downward against the spring 34 to adapt the apparatus for different sized bowls. 36 is a standard similar to standard 33, provided with a slidable, rectangular retaining block 37 adapted to clamp down 105 the cross-head 29 under action of a nut 38 threaded upon the reduced upper end of standard 36, or, upon the releasing of said nut, to be turned lengthwise of the cross-head 29 to permit the bars of the latter to 110

clear said block and be lifted past it. The bars constituting the cross-head 29 are curved outward around the stem of the inverted bowl 34 and thus are adapted to bear upon the wooden annulus 26.

- In the operation of the device the rubber stock which is to constitute the lining of the bowl is placed in the latter by hand and pressed against its walls sufficiently to retain it therein, and is folded over the bowl's rim as indicated at 25, Fig. 2. The device is opened by releasing the nut 38, turning the block 37 lengthwise of the cross-head 29 and turning the latter upward about its hinge 31. The wooden annulus 26 and guard 27 attached thereto are removed by the handle 28. The bowl, 22, with the rubber lining loosely retained therein, is then inverted over the bag 14 and allowed to rest upon the annular plate 20, within the guard 21. The cross-head 29 is then turned back, upon its hinge 31, until it rests upon the annulus 26, and is clamped in that position by means of the block 37 and nut 38. Compressed air or steam is then admitted to the interior of the bag 14 through the pipe 13 and the hole 11^a in the block 11, expanding the bag 14 against the lining 24, pressing the latter firmly against its walls with substantially equal pressure at all points, compacting said lining and causing it to adhere to the walls of the bowl and to enter the perforations 23 therein, and thus interlocking it with the metal bowl. In order to avoid the forming of dimples in the inner face of the lining due to the flow of rubber into the perforations, plugs 24^a of rubber stock may be inserted into said perforations from the outside of the bowl, to coalesce with the lining stock during the pressing and the subsequent vulcanizing operation. After vulcanization small holes are bored through the rubber which fills the perforations 23. In Fig. 5 the lining and one of the plugs are shown as having consolidated, and the hole bored therethrough is shown at 23^a.

The reinforcing plate 17 prevents the bag 14 from unduly swelling out into the hollow stem of the bowl. The internal diameter of the annular plate 20 being somewhat larger than the bag 14, the latter is permitted to bulge out adjacent said plate and thus slightly round the corner of the lining 24 at that point. The relatively large internal diameter of the plate 20 also facilitates the removal of the plate past the bag 22. The guards 21, 27 prevent injury to the operator in case the bowl is exploded by the internal fluid pressure. The block 11 prevents the bag 22 from collapsing between operations, holds it in suitable shape for the placing of the bowl over it, and insures a direct application of each part of the bag to the adjacent part of the lining.

Various modifications may be resorted to

without departure from the scope of my invention, and I do not wholly limit my apparatus claims to the specific construction shown. The process may also be carried out in various ways although preferably performed with a device having substantially the features herein described.

I claim:

1. The method of lining a hollow structure with a plastic material which comprises placing a sheet of said material within the structure, pressing it lightly against the wall of the latter to cause it to adhere thereto, and applying fluid pressure to said plastic material.

2. The method of lining a hollow structure with a plastic material which comprises placing a sheet of said material within the structure, and distending a flexible member against said material by fluid pressure to compress it against the wall of said structure.

3. The herein-described method which comprises applying a plastic lining to a rigid structure having a broken surface, and forcing it by fluid pressure into interlocked engagement with said surface.

4. The method of lining a hollow, foraminous, metal structure which comprises applying a plastic lining to said structure, and forcing said lining outwardly into interlocked engagement therewith by means of internal fluid pressure.

5. The method of making rubber-lined structures which comprises applying a lining of hard-rubber compound to a foraminous metal bowl, and forcing said lining outwardly into interlocked engagement with said bowl by means of internal fluid pressure.

6. The method of lining foraminous metal bowls which comprises applying a plastic lining to the bowl, placing the latter over an expandable bag having substantially the shape of the interior of said bowl, inflating said bag, and thereby forcing the lining outwardly into interlocked engagement with the bowl.

7. The method of lining a perforate structure with plastic material which comprises inserting plugs of said material into the perforations of said structure, placing a sheet of said material within the structure, and compressing said sheet of material against the wall of said structure by fluid pressure.

8. The method of making a rubber-lined spinning bowl which comprises plugging the perforations of said bowl with a rubber compound, placing a sheet of rubber compound within said bowl, pressing said sheet against the wall of said bowl by fluid pressure, subjecting said bowl to vulcanizing heat, and drilling holes through the vulcanized rubber compound within its perforations.

9. A device for pressing a lining in a vessel comprising a form having substan-

- tially the shape of the interior of the vessel and adapted freely to receive the vessel thereover, and a bag adapted to be expanded from said form against said lining.
5. 10. A device for pressing a lining in an open-ended vessel comprising a base, means for holding the vessel in inverted position upon said base, and means for supplying fluid under pressure to the interior of said vessel.
11. A device for pressing a lining in an open-ended vessel comprising a base, a bag having its mouth sealed to said base and adapted freely to receive the vessel thereover, means for holding an inverted vessel upon said base over said bag, and means for distending said bag.
12. A device for pressing a lining in a vessel comprising a base, a bag having its margin sealed to said base, means for holding an inverted vessel upon said base over said bag, means for distending said bag, and a shield adapted to surround said vessel.
13. A device for pressing a lining in a vessel comprising a base, a removable annulus for holding an inverted vessel upon said base, means for applying fluid pressure to the interior of said vessel, and a shield secured to said annulus.
14. A device for pressing a lining in a vessel comprising a base, a bag having its margin sealed to said base, an annular member adapted to encircle said bag and rest upon said base, a shield secured thereto, an annular member adapted to rest upon an inverted vessel to hold the same upon said base, a shield secured to the last said
- annular member, and means for distending said bag.
15. A device for pressing a lining into a spinning bowl comprising a base, a form mounted on said base, a bag mounted upon said form and secured at its margin to said base, an annulus adapted to rest upon a vessel inverted over said form, a shield secured to said annulus, a cross-head adapted to bear upon said annulus, and means for introducing fluid pressure to the interior of said bag.
16. A device for pressing a lining in a vessel comprising a flexible, substantially hat-shaped, elastic bag adapted to be inflated against said lining, said bag having stiffening reinforcement in the top wall thereof adapted to prevent the deformation of said wall of the bag.
17. A device for pressing a lining in an open-ended vessel comprising a base, an inflatable bag mounted on said base, and means for holding an inverted vessel upon said base over said bag, said means comprising an adjustable block, and a lever pivoted to said block.
18. A device for pressing a lining in a vessel formed with a recess from its main cavity comprising a bag adapted to be distended within said vessel, and a stiffening reinforcement in the wall of said bag adapted to restrict deformation of said wall into said recess.
- In witness whereof I have hereunto set my hand this 1st day of June 1921.
- 70
- FRANK J. MACDONALD.
